CLOSURE FOR COLLAPSIBLE TUBES

John Lewis Hudson, Vancouver, British Columbia, Canada

Application May 31, 1939, Serial No. 276,565

5 Claims. (Cl. 221—60)

My invention relates to improvements in closures for collapsible tubes, which are adapted particularly for tooth pastes, face creams and the like. The objects of the invention are to provide a tube which may be incorporated in the conventional screw cap of a tube itself or may be incorporated as an integral part of the tube, which will enable a thin ribbon of paste of uniform width to be extruded as the tube is squeezed. A further object is to provide a closure which when incorporated in the tube structure will be so economical to manufacture and assemble that its cost of production will be practically the same as that of the conventional tube with its cork washer and screw cap.

The invention consists essentially of a closure in the form of a spring loaded valve having a rectangular head closing onto a seat formed on one side only of the valve head, as will be more fully described in the following specification and shown in the accompanying drawing, in which:

Fig. 1 is a sectional view of a collapsible tube fitted with the invention.

Fig. 2 is a sectional view taken at right angles to Figure 1.

Fig. 3 is a plan view looking up at the underside of the valve stem.

Fig. 4 is a front elevational view of a modified form of valve locking means.

Fig. 5 is a side elevational view of the modification.

In the drawing like characters of reference indicate corresponding parts in each figure.

The numeral 1 indicates a collapsible tube having a nipple 2 of substantially cylindrical form, which is bevelled as at 3 on one side of its upper face 4. The nipple 2 is provided with a rectangular axial bore 5 and is provided on one marginal edge with a bevelled seat 6.

Slidably mounted within the bore 5 is a valve generally indicated by the numeral 7, which consists of a stem 8 having two sides and one rear wall indicated by the numerals 9 and 10 respectively, which define a passage 11. The walls 9 and 10 support a head 12 which is preferably bevelled on its underside as at 13 and terminates with a lip 14 which closes upon the seat 6. The lower extremities of the stem walls 9 are provided with tongues 15 which are adapted to be bent outwardly as shown, to support a washer 16. The valve 7 is normally held closed by a spring 17 surrounding its stem 8 and abutting the underside of the nipple 2 and the upper surface of the washer 16. Should it be desired to lock the valve 7 in closed position, to prevent inadvertent ex-

trusion of paste, I provide a U-shaped wire bail 19 having inturned terminal ends 20 which are sprung into complementary recess 21 formed in the sides of the nipple. By providing loops 22 in the bail 19 extending above the top of the nipple and beyond its diameter, I provide a flexibility to said bail which permits it to be sprung into locking position with ease.

In the modification shown in Figures 4 and 5, the valve head 12 is locked when desired with a U-shaped bail 25 having inturned legs 26 which are slidable within a pair of horizontal grooves 27 to move into and out of valve head engaging position.

If a locking bail such as 19 or 25 is fitted to the tube when bought, such bail will first be moved away from contact with the valve head 12. Should the purchaser not have further need for any locking device, which is only of value when carrying the tube in a travelling case, it may be easily pried off.

To dispense paste from the tube, it suffices to squeeze the tube, thus forcing the valve off its seat and causing a ribbon of paste to flow between the lip 14 and the seat 6. By virtue of the fact that the seat 6 extends on one side only of the bore 5 and that the ends of the lip 14 of the head are never entirely raised above the body of the nipple 2, the ribbon formed by the paste in discharging is maintained at a constant width and the valve on closing cuts off the ribbon of paste, leaving the nipple quite clean and free from adherent paste. It is of course assumed that the tube is held in a substantially horizontal or an inverted position when dispensing paste therefrom.

What I claim as my invention is:

1. A closure for collapsible tubes comprising a nipple having a bore through which the contents of the tube are adapted to be expressed, said bore being provided at its outer end and on one side only with a bevelled seat; a valve consisting of a vertically grooved rectangular stem slidable in the bore and a head upon the stem, said head being adapted to close the bore of the nipple and being provided with a bevelled lip projecting beyond one side of the bore adapted to close against the seat and spring means for closing the valve.

2. A closure for collapsible tubes comprising a nipple having a rectangular bore through which the contents of the tube are adapted to be dispensed, said bore being provided on one side of the rectangle with a bevelled seat, a valve slidable within the bore, said valve having a stem substantially fitting the bore and being substantially

- U-shaped in cross section and a head upon the stem, said head having a lip adapted to close upon the seat and means for retracting the valve to close it.
5. 3. A closure for collapsible tubes comprising a nipple having a rectangular bore through which the contents of the tube are adapted to be dispensed, said bore being provided on one side of the rectangle with a bevelled seat, a valve slidable within the bore, said valve having a stem formed with side and rear walls substantially fitting the bore, and a head upon the stem, said head having a lip adapted to close about the seat, said walls being provided at their lower ends with tongues, 10 a spring surrounding the lower end of the stem, a washer at the base of the spring, said tongues being outwardly bent to support the washer upon the stem.
15. 4. A closure for collapsible tubes comprising a
- nipple having a bore through which the contents of the tube are adapted to be expressed, said bore being provided at its outer end and on one side only with a seat, a valve consisting of a stem 5 slidable in the bore and a head upon the stem, said head being adapted to close the bore of the nipple and being provided with a lip adapted to close against the seat, and spring means for closing the valve, and means carried by the nipple and movable substantially in the plane of the surface of the valve head for locking the valve against opening.
10. 5. A closure for collapsible tubes as claimed in claim 4 wherein the locking means comprises a substantially U-shaped member having inturned 15 terminal ends engaging the nipple and having a pair of loops formed in the U-shaped member.

JOHN LEWIS HUDSON.
